UNITED STATES PATENT OFFICE.

WILLIAM C. ANDERSON, OF TOLEDO, OHIO.

DESIGN FOR A GLASS DISH.

SPECIFICATION forming part of Design No. 25,512, dated May 19, 1896.

Application filed March 19, 1896. Serial No. 583,983. Term of patent 7 years.

To all whom it may concern:

Be it known that I, WILLIAM C. ANDERSON, a citizen of the United States, residing at Toledo, in the county of Lucas and State of Ohio, 5 have invented and produced a new and original Design for the Ornamentation of a Glass Dish, of which the following is a specification.

This design relates to glassware ornamentation, and particularly to cut-glass dishes, 10 the design usually being applied to the exterior surface of such dishes which are usually of pronounced concavity, although this design is equally applicable to dishes of a comparatively shallow type.

15 The drawings consist of two figures, Figure 1 representing the complete design, and Fig. 2 a section of a portion of a dish to which the design has been applied.

This design consists, essentially, of a large 20 square-shaped figure having the incurved sides *a* and a small square centrally inclosed by said larger square, the sides of said central square *b* being each prolonged to a point intersecting the incurved sides of said large 25 square, from which point said lines are first outwardly and then inwardly curved until they meet at a central point near the edge of the dish, forming a so-called "ogee" arch-shaped figure *d* midway between the corners 30 of said large square. The prolongation of the sides of the small square to points intersecting the sides of the larger inclosing square results in the formation of the parallelograms *e* opposite each face of the small square, and

also results in the formation in each of the 35 corners of the large square and between the ends of said parallelograms *e* of diamond-shaped figures *f*, one end of which is drawn out to meet the intersection of two of the said incurved sides of said larger square. The 40 corners of said large square and substantially the center of the sides of said ogee arches are joined by a straight line *o*, giving that part of the design just described the appearance of overlying an octagonal figure. Within each 45 of the ogee arches is a rosette, and springing from the lines *o*, forming the octagonal figure above described between the said arches around the edge of the dish, are groups of radial lines whose outer edges are dentilated. 50 Said small central square, said parallelograms, and said diamond-shaped corner-figures are variously ornamented, as shown in the drawings, by small hexagonal figures and diamond-shaped figures, and the triangles *m*, formed 55 by the lines of the octagonal figures, and the sides of said ogee arches and said incurved sides of the large square, are ornamented by cross-hatching.

What I claim is—

60 The design for ornamentation of a glass dish, substantially as herein described and shown.

WILLIAM C. ANDERSON.
